UNITED STATES PATENT OFFICE.

HYMAN MAIMIN, OF NEW YORK, N. Y., AND WILLIAM J. MARSHALL, OF NEWARK, NEW JERSEY, ASSIGNEES TO H. MAIMIN CO., INC., A CORPORATION OF NEW YORK.

KNIFE-DRIVE FOR CLOTH-CUTTING MACHINES.

1,292,625.

Specification of Letters Patent. Patented Jan. 28, 1919.

Application filed November 17, 1917. Serial No. 202,562.

To all whom it may concern:

Be it known that we, HYMAN MAIMIN and WILLIAM J. MARSHALL, both citizens of the United States, said MAIMIN residing in the 5 city, county, and State of New York, and said MARSHALL residing in Newark, county of Essex, and State of New Jersey, have invented certain new and useful Improvements in Knife-Drives for Cloth-Cutting Machines; and we do hereby declare the following to be a full, clear, and exact description of the invention, such as will enable others skilled in the art to which it appertains to make and use the same.

15 The invention relates to improvements in cloth cutting machines of that type in which a vertically reciprocating cutting knife is driven by a rotary motor, as, for example, an electric motor having a rotating armature.

20 In machines of this type, as now commonly employed, the knife is driven at very high speeds in order that the cutting operation may proceed rapidly and effectively. These speeds run as high as three thousand 25 revolutions per minute of the armature shaft, and this shaft is directly connected to the knife to produce three thousand complete up and down strokes per minute. The knife is made as thin as is consistent with 30 good cutting and a portion of the blade is incased in a knife sheath or slot within the uprising standard of the cloth cutting machine. Inasmuch as the resistance to the forward movement of the knife through the cut 35 cloth increases with any increase in thickness of the knife and of the incasing standard, it is highly important that the knife should be thin and that the sheath should fit it closely. On the other hand, if, for any reason, the 40 blade of the knife comes into contact with the wall of the sheath, the high speed will immediately give rise to a destructive heating and wearing of the knife blade. It has been the common practice to fasten the knife 45 in the lower end of a vertically reciprocating holder, which holder is driven from the rotating motor through a crank and pitman, and the pitman has usually been connected at its lower end either directly to the knife 50 holder or to a suitably guided crosshead attached to the upper end of the knife holder. In these constructions, the arrangement has been such that the lateral thrust of the pitman has been taken up by some vertical guiding surface. When these machines 55

are in use the down stroke is of the nature of a chopping stroke in that the lower or horizontal cutting edge of the knife is forced downwardly through the cloth. In other words, the driving pitman is required to impart a violent thrust or blow to the driven knife holder just at the beginning of the downward stroke, and it has been found in practice that this has resulted in marked localized wear of the vertical guideways. As 60 soon as this wear becomes evident, it results in a certain amount of play at that part of the guideways and is accompanied by a violent vibration of the entire cutting machine, so that the accuracy of the cutting is interfered with and the wear rapidly progresses to a point where the machine has to be repaired.

It is the object of the present invention to overcome these difficulties by providing a 75 driving connection between the knife and the motor of such character that a thin knife closely embraced by the sheath in the standard may be rapidly driven, and yet may be so guided, and may have the driving force 80 so applied to it, that the knife will not contact with the wall of the sheath and the wear and tendency toward lateral movement, due to the above described thrust, is done away with. To that end, we have adopted the mechanical construction and arrangement illustrated in the drawings and hereinafter described. The foregoing remarks, together with the description of the specific embodiment shown, will make clear the principles 85 of the invention, and it will be understood that the mechanical elements described may take many equivalent forms without departing from the spirit of the invention.

In the drawings, Figure 1 is a front view 95 of a cloth cutting machine equipped with the knife-driving mechanism of our invention, the front plate of the machine being removed; Fig. 2 is a side elevation partly broken away to disclose the driving mechanism, and Fig. 3 is a plan view of the front portion of the machine likewise broken away to disclose the driving mechanism.

The machine has the usual foot plate 1 and standard 2 which supports the driving 105 motor 3 and is provided with an operating handle 4. As is customary, the rear portion of the knife blade 5 is closely embraced by a groove or sheath in the standard 2, as shown in dotted lines in Fig. 2, and the 110

knife and sheathing standard are made as narrow as is consistent with good cutting and rigidity, for the purpose above described.

5 In accordance with our invention there is connected to the upper end of the knife 5 a driving rod 6 which should be of ample strength and rigidity as shown. This rod is rigidly secured at its upper end to a cross-head 7 which is provided with a transverse slot or groove 8 to receive a crank pin 9 extending from a crank or crank disk 10 secured to the end of the shaft of the electric motor 3. It will be observed that the 10 construction and arrangement of this cross-head is such that only the downward thrust of the crank pin, and not the lateral thrust, is imparted to the crosshead. The crosshead 7 is guided in its vertical movement by suitable guides which are here shown in the 15 form of a pair of vertically extending rods or pillars 11 embraced by integral wing portions 12 of the crosshead.

This construction provides for the exact 20 vertical guiding of the crosshead without subjecting the guides to localized wear due to the lateral thrust above described, but for the purpose of further insuring the true running of the knife blade, we prefer to provide an additional guideway for the rod 6 25 between the crosshead and the point where the rod is connected to the knife. To this end we have inserted within the front portion of the frame of the machine a guide block 13 containing a centrally located bore through which the rod 6 passes and in which it closely fits. This block may be as long as 30 is found necessary to accurately guide the rod 6 so as to entirely insure the perfectly 35 true running of the knife within its sheath. In the construction shown, the bars or pillars 11 are anchored at their lower ends in 40 this block, but it will be understood that if preferred these bars or pillars 11 may be 45 anchored in the permanent frame of the machine itself.

It will, however, be observed that in the preferred construction here illustrated the bars or pillars 11 are positioned in front of 50 and on opposite sides of the bore through the guide block 13, so that lines joining the centers of these three guiding elements form a triangle. This construction is adopted for the purpose of affording great rigidity of 55 the guiding means against any thrust tending to move the knife back and forth in its own plane and it supplements the above described means of preventing lateral vibra-

tion to provide a complete rigidity of the entire guiding mechanism.

60

What we claim is:

1. A cloth cutting machine having a reciprocating knife and a closely embracing sheath therefor, in combination with driving and guiding means for the knife comprising a driving rod connected at its lower end to the knife, a crosshead rigidly secured to the upper end of the rod and having a transverse slot to receive a crank pin, a rotary driving motor, a crank connected with the shaft of the motor and provided with a crank pin engaging the slot in the crosshead, and a pair of rigid vertical guides for the crosshead located on opposite sides of the motor shaft; substantially as described. 75

2. A cloth cutting machine having a reciprocating knife and a closely embracing sheath therefor, in combination with driving and guiding means for the knife comprising a driving rod connected at its lower end to the knife, a crosshead rigidly secured to the upper end of the rod and having a transverse slot to receive a crank pin, a rotary driving motor, a crank connected with the shaft of the motor and provided with a crank pin engaging the slot in the crosshead, a pair of rigid vertical guides for the crosshead located on opposite sides of the motor shaft, and a supplemental guide for the driving rod located between the crosshead and the point where the rod is attached to the knife. 80

3. A cloth cutting machine having a reciprocating knife and a closely-embracing sheath therefor, in combination with driving and guiding means for the knife comprising a driving rod connected at its lower end to the knife, a crosshead rigidly secured to the upper end of the rod and having a transverse slot to receive a crank pin, rigid vertical guides for the crosshead, a rotary driving motor, and a crank connected with the shaft of the motor and provided with a crank pin engaging the slot in the crosshead, together with a supplemental guide for the driving rod located between the crosshead and the point where the rod is attached to the knife, the vertical guides and the supplemental guide being so positioned that lines joining their centers form a triangle, substantially as described. 100

In testimony whereof, we affix our signatures.

HYMAN MAIMIN.
WILLIAM J. MARSHALL.
